Primary Examiner — Jonathan J Han*Assistant Examiner* — Yuan Yuan(74) *Attorney, Agent, or Firm* — Minder Law Group;
Willy H. Wong(57) **CLAIM**

The ornamental design for a cat bubble toy, as shown and described.

DESCRIPTION

FIG. 1 is a front view of a cat bubble toy in accordance with the present invention.

FIG. 2 is a rear view thereof.

FIG. 3 is a left side view thereof.

FIG. 4 is a right side view thereof.

FIG. 5 is a top view thereof; and,

FIG. 6 is a bottom view thereof.

The broken lines show portions of the cat bubble toy that form no part of the claimed design.
